UNITED STATES PATENT OFFICE.

ZENAS BELDON LEONARD, OF CLEVELAND, OHIO.

METAL-HEATING FURNACE.

1,241,526.

Specification of Letters Patent.

Patented Oct. 2, 1917.

Application filed May 20, 1916. Serial No. 98,720.

To all whom it may concern:

Be it known that I, ZENAS BELDON LEONARD, a citizen of the United States, residing at Cleveland, in the county of Cuyahoga and State of Ohio, have invented certain new and useful Improvements in Metal-Heating Furnaces, of which the following is a specification.

My invention comprises a heating furnace embodying means to convey numerous strips of metal collectively or in batches through the heating chamber thereof, including a device to deliver the strips in definitely assembled relation in batches to said conveying means, and also a device to remove and carry away each batch of strips subsequent to the heating operation. The invention is especially applicable to the heating of narrow flat strips or plates of different lengths adapted to form a laminated vehicle spring, and to be used with cambering and quenching apparatus arranged in near proximity to the discharge end of the furnace.

In the accompanying drawings, Figure 1 is a horizontal section of the furnace on line 1—1, Fig. 2, and Fig. 2 is a longitudinal section on line 2—2, Fig. 1. Fig. 3 is a transverse section of the furnace on line 3—3, Fig. 2, showing the metal strips elevated above the floor of the furnace, and Fig. 4 is a cross section on line 4—4, Fig. 1, showing the discharge end of the furnace with the metal strips deposited on the transverse carrier and with the horizontal transfer elevator in a lowered position.

The furnace consists of an elongated brick structure 2 subdivided horizontally by a false bottom 3 to provide chambers and compartments above and below the same. Thus, one end of the furnace has a receiving chamber 4 separated from a central heating chamber 5 which communicates with a discharge chamber 6 at the opposite end of the furnace, both end chambers 4 and 6 being cut off from the heating chamber 5 by depending baffle walls 7 extending into close proximity to bottom 3, but with sufficient space therebetween to permit the passage of the material into and out of the chamber. A number of gas or oil burners 9 are arranged at intervals at one side of the furnace to furnish the desired heat for heating the material which is caused to travel longitudinally through chamber 5 by the means hereinafter described, and a vertical flue or a

series of flues 10 in the arched roof 11 permit the products of combustion to escape. The wall 3 forming the bottom of heating chamber is divided longitudinally by parallel slots 12 extending the full length of the furnace and the intermediate sections of said wall 3 between the slots are supported by I beams 13 resting at their ends in the end walls of the furnace and supported at intermediate points by piers or cross walls 14, and a fabricated metal frame composed of parallel beams 15 and 16 of channel iron united by cross pieces 17, is arranged beneath floor or bottom 3 in the base compartments 5' to support stringers or rows 18 of fire brick in the slots 12, whereby the strips of metal 19 which are to be heated may be lifted and conveyed through the furnace. In brief, the metal and brick frame described provides a transfer device in conjunction with means to raise and lower and reciprocate the same, the means for this purpose in the present instance comprising cams 20 on transverse shafts 21 operated by bevel gears 22 and a power shaft 23 located outside of the furnace walls, including a crank shaft 24 driven by bevel gears 25 from power shaft 23. The cams raise and lower beams 15 and the crank imparts a reciprocal movement to said beams through connecting links 26, but any other suitable operating mechanism may be used, whereby both vertical and longitudinal movements may be given to the supporting stringers 18 to carry the stock step by step longitudinally through the furnace.

Feeding of the stock and discharge thereof is obtained by similar movable carriers 27 and 28 adapted to travel transversely within the end chambers 4 and 6 of the furnace. These carriers comprise curved forks suspended by rollers from overhead tracks 29 and the prongs or branches of the forks are spaced apart to permit the stringers 18 to be raised thereinto when either carrier is at rest in its respective end chamber. When this occurs with a loaded carrier 27 in receiving chamber 4 the batch of strips 19 thereon are lifted from the prongs by the stringers 18 and moved collectively as pre-arranged into the heating chamber 5 by a forward movement of the stringers, vertical uplift being obtained by the cams 20 preliminary to a forward movement by the crank shaft 23. When the limit of forward movement of the stringers is reached

the cams lower the stringer frame and the batch of strips 19 are deposited on the floor 3 within the heating chamber where they remain until the stringers are elevated in the next cycle of movement to raise and carry the same batch of strips a definite distance farther inward into the heating chamber for deposit on the floor in the same way. This transfer occurs repeatedly not only with one 10 batch of strips but with all the batches in the furnace and each batch upon entering the discharge chamber 6 is deposited on the prongs of a carrier 28 awaiting to receive them. Following a lowering movement of 15 the stringers, carrier 28 with its load is drawn or pushed out of chamber 6 upon the inclined portion 30 of track 29 to discharge the strips by gravity upon cambering dies in a cambering and quenching machine, not 20 shown. The same carrier is then returned to its proper place in end chamber 6 to take the next batch of strips discharged by stringers 19, or a series of such carriers may be arranged to travel successively through 25 the chamber for this purpose, especially where openings are provided at opposite sides as shown in the receiving chamber 4 where successive delivery of separate batches 30 of strips is adapted to proceed by a series of carriers traveling in the same direction. The construction of the apparatus is such that all the different length strips that enter into a single laminated vehicle spring may be conveyed collectively through the furnace 35 and delivered to a cambering and quenching machine without disturbing their assembly, and with the substantial advantage of having all the strips of each batch heated and treated exactly alike. Uniformity in 40 production is one result, the output large, and the operations effected with speed and considerable economy as compared with present practices.

What I claim is:

45 1. A furnace having a heating chamber and means to convey strips of metal of different lengths in separate batches in pre-arranged alinement through said furnace, in combination with means to receive each 50 batch of strips successively from said conveying means and means to project the strips endwise from said receiving means into other treating apparatus.

2. A furnace having a device to deliver a batch of metal strips in pre-arranged separated relation thereinto, means to convey each batch of strips as pre-arranged step by step through the furnace, means to remove each batch of strips collectively in separated relation from the furnace and means to discharge each batch of strips endwise to other apparatus. 55 60

3. A furnace having a conveyer located therein for feeding groups of metal strips of different lengths therethrough in the horizontal plane and with the strips of each group separated, means to deliver each group of strips to said conveyer in pre-arranged separated and staggered relation, and means to remove each group of strips 70 from said conveyer in the same arrangement and order as delivered to the furnace. 65

4. A heating furnace having a heating chamber, a horizontal conveyer extending through and beyond each end of said chamber, and conveyers at each end of said chamber having means to co-act with said horizontal conveyer to transfer a plural number of metal strips alined in definite pre-arranged relation in separate groups successively through the furnace. 75 80

5. A heating furnace having a conveyer comprising parallel supports longitudinally movable therein for the material to be heated, elevated tracks extending into opposite ends of said furnace transversely of said conveyer, and conveyers suspended from said tracks having fingers extending longitudinally of said first conveyer between said parallel supports. 85 90

6. A heating furnace having a conveyer in its bottom for the material to be heated, in combination with an elevated track at one end of the furnace having an inclined portion, and a carrier suspended from said 95 track having prongs to co-act with said conveyer to receive the material from said conveyer and to be tilted by the inclined portion of the track.

In testimony whereof I affix my signature 100 in presence of two witnesses.

ZENAS BELDON LEONARD.
